US0D1070411S

(12) United States Design Patent (10) Patent No.: US D1,070,411 S
(45) Date of Patent: * Apr. 15, 2025

(54) SILICONE STORAGE BOX

(71) Applicant: Dongguan Nanhong Electronic Technology Co., Ltd., Guangdong (CN)

(72) Inventor: Mingzhong Zhou, Guangdong (CN)

() Term: 15 Years

(21) Appl. No.: 29/977,551

(22) Filed: Dec. 9, 2024

(51) LOC (15) Cl. 08-08

(52) U.S. Cl.

USPC D6/553

(57) CLAIM

The ornamental design for a silicone storage box, as shown and described.

DESCRIPTION

FIG. 1 is a front, right and top perspective view of a silicone storage box showing my new design;

FIG. 2 is a front, right and bottom perspective view thereof;

FIG. 3 is a rear, left and top perspective view thereof;

FIG. 4 is a front view thereof;

FIG. 5 is a rear view thereof;

FIG. 6 is a left side view thereof;

FIG. 7 is a right side view thereof;

FIG. 8 is a top view thereof; and,

FIG. 9 is a bottom view thereof.

1 Claim, 9 Drawing Sheets
